UNITED STATES PATENT OFFICE.

J. HOWARD HAND, OF ASTORIA, NEW YORK.

CARTRIDGE-LOADING IMPLEMENT.

SPECIFICATION forming part of Letters Patent No. 236,678, dated January 18, 1881.

Application filed October 28, 1880. (No model.)

To all whom it may concern:

Be it known that I, J. HOWARD HAND, of Astoria, in the county of Queens and State of New York, have invented a certain new and 5 useful Improvement in Cartridge-Rammers, of which the following is a description, reference being had to the accompanying drawings, where—

Figure 1 is a side view of a common cartridge-rammer in position for forcing a wad into a brass shot-shell, (for use in breech-loading shot-gun,) the shell and the funnel represented as cut in central vertical longitudinal section. Fig. 2 is a similar view of my improved 15 cartridge-rammer. Fig. 3 is a view of the lower end of my improved cartridge-rammer.

It is well known to users of breech-loading shot-guns that in loading the shells therefor wads must be used one or two sizes larger in 20 diameter than the bore of the shell, in order to have the wads pack tightly into the shell. A No. 10 wad is usually used for a No. 12 shell. To enable such a wad to be introduced into the shell a funnel, *a*, is made use of. The common rammer *b* is of substantially the same diameter (slightly less, of course) as the bore of the shell *c* itself. The result of its use is that the wad is more or less broken and turned up on the edge, on one side or the other, offering 25 unequal resistance to the escape of the gases when the powder explodes, increasing the tendency of the wad to turn edgewise in the shell or gun when forced out, with consequent loss of force and accuracy in the charge, and making 30 the wad liable to become loose in the shell by carriage thereof, or by the concussion incident to the explosion of a charge in a neighboring barrel. These and other difficulties are incident to the use of the common cartridge-rammer.

My invention consists, primarily, in giving the rammer an elastically-expansible end, so that at its first contact with the wad it may be diametrically of the same size as the wad, 45 and therefore cover the whole upper surface of the wad, and, contracting by contact with the funnel and the interior of the shell, continue to cover the whole wad during its progress downward through the funnel and into

the shell, until it is set home to its place, 50 thereby preventing the edge of the wad from being broken or turned up at one point or another, and setting the wad home with like and equal pressure at all points, and remedying the difficulties incident to the use of the common rammer. 55

I show this improvement embodied in a wooden rammer, *d*, in Figs. 2 and 3. The radial movability of the end of the rammer, which comes in contact with the wad, is attained by 60 making the slots *e*, dividing the rammer, into sections *d'*, the elasticity of which is given by the natural elasticity of the wood. It is well to also bore the central hole, *f*. In order to have this end of the rammer round when compressed by being inserted into a shell, the central hole, *f*, may be bored and the cross-slots *e* made before the rammer is turned in a lathe, and the sections compressed and bound while the turning is being done. 65

It is necessary that the exterior surface of my improved rammer should have a slight continuous taper from the base or lower end to a point opposite the upper ends of the slots *e*, in order that the expansible portion may 70 properly enter the funnel and shell, and from the point opposite the upper ends of the slots to the enlarged head the exterior surface of my rammer may continue to taper, or be cylindrical with a diameter nearly that of the shell, so that after the expansible portion has 75 entered the remaining portion above, it may be exactly centered over the wad, and fit snugly within the shell without lateral play, to insure the pressure, when applied to the head, being 80 uniformly distributed upon the wad, thus avoiding the liability of the wad being tipped and seated in an angular position upon the charge 85 incident to cartridge-rammers as heretofore constructed.

This improvement may be readily embodied in metal by making the rammer of a tube divided into sections the same as the wooden rammer, with appropriate ends fastened to the sections and the sections sprung radially outward. The wooden rammer can be made more durable by facing the sections with thin brass. 95

I am also well aware that there are other

methods of attaining radial expansibility of the end of the rammer than the specific methods herein described.

I claim as my invention—

- 5 A cartridge-rammer slotted at its lower end, and with a slight continuous taper on the exterior surface of its slotted portion, which is otherwise smooth and unbroken, and with a

central hole extending up therein, in combination with a funnel or guide, *a*, for directing it axially, to enable it to squarely seat the wad within the shell, substantially as described.

J. HOWARD HAND.
